DAVID ADDISON FERRIS, OF ITHACA, NEW YORK.

GLUING-CLAMP.

1,162,759.

Specification of Letters Patent.

Patented Dec. 7, 1915.

Application filed January 11, 1915. Serial No. 1,683.

To all whom it may concern:

Be it known that I, DAVID A. FERRIS, a citizen of the United States, residing at Ithaca, in the county of Tompkins and State of New York, have invented a new and useful Gluing-Clamp, of which the following is a specification.

This invention has reference to gluing clamps, and its object is to provide a clamp structure of practically universal applicability whereby a relatively large number of articles consisting of parts glued together may be clamped at one time in one structure, thereby avoiding the use of a large number of clamps which have heretofore been found necessary for a like purpose.

Where two pieces of wood, say, two boards or strips, are to be glued together edge to edge, it is customary to employ two or three or more clamps to hold these boards in close edge to edge union until the glue has set. Where a large variety of pieces are glued together the necessary stock of clamps is correspondingly large and the work necessarily takes up a large amount of space.

With the present invention there is provided a single structure capable of receiving and holding a large amount of work, whereby a great variety of gluing may be proceeded with at the same time and occupy a minimum of space during the period of rest when the parts are clamped firmly together and so remain until the glue has set. Moreover, the present invention provides a skeleton frame structure capable of being dismantled to occupy a minimum of space when not in use, and which may be set up to accommodate various lengths, widths, and thicknesses of material and to hold such material with the parts in firm union during the gluing operation.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is a perspec-

tive view of the gluing clamp frame ready for the application of the material to be glued, the spacing strips and other parts being omitted. Fig. 2 is a longitudinal vertical section with some parts in elevation showing the gluing clamp structure with some work in position. Fig. 3 is a top plan view of one end of the structure of Fig. 2, said end being the left hand end as viewed in Fig. 2. Fig. 4 is a section on the line 4—4 of Fig. 3. Fig. 5 is a bottom plan view of one of the sills and some of the cross strips of the clamp. Fig. 6 is a perspective view of one of the spacing strips or bars.

Referring to the drawings there is shown a basic frame consisting of longitudinal sills or beams 1 joined by a sufficient number of cross strips 2. Each beam or sill 1 on the edge facing the other beam or sill has a longitudinal groove 3 therealong. Adapted to extend from one beam to the other and movable lengthwise therealong are other cross strips 4 each provided near each end with an angle clip 5 made fast to the strip 4 and shaped to enter a corresponding one of the grooves 3 so that the strips 4 may be moved lengthwise of the beams 1 without liability of escape therefrom. Each strip 4 is provided with a longitudinal series of holes or perforations 5^a and each perforation 5^a is entered by a passage 6 extending from one edge of the strip 4. Adapted to any one of the passages 5^a are posts 7 having perforations 8, 9, at the respective ends for the reception of pins 10 each having a manipulating head 11 for convenience of handling. These pins need not of necessity be specially formed pins, since certain sizes of wire nails are well adapted for the purpose. Each post 7 is preferably made of metal pipe but may, of course, be made solid, or of other material than metal, and while it is customary to form the beams, bars and strips of the clamping frame of wood, it will be understood that they may be made of metal, and especially structural metal. However, as it is quite usual to make structures either of wood or of appropriate angle metal, and sometimes sheet metal stiffened by appropriate flanges, it is deemed unnecessary to illustrate the various ways of constructing the frame and the illustration is therefore confined to a wooden frame with tubular posts. Each strip 4 is usually provided with at least two posts 7 at the oppo-

site ends, which posts, however, may be placed at any points along the strips 4 permitted by the holes 5^a. The ends of the strips 4 rest upon the top faces of the beams 1 and these strips are held to the beams by the clips 5, so that the strips may be moved lengthwise of the beams to any desired extent. The cross strips 2 are spaced from the strips 4 and in the spaces thus provided there is lodged a longitudinally disposed beam 13 which may be, though it is not necessarily longer than the beams 1, and this beam 13 is slidable both lengthwise and crosswise of the basic frame made up of the beams 1 and cross strips 2, and is confined to the cross strips 2 supporting it by the overriding cross strips 4. Erected on the beam 13 at the ends thereof are posts 14 connected together at the upper ends by another beam 15. The posts 14 are connected to the beam 13 by pins 10 and the beam 15 is connected to the post 14 at the upper ends thereof by pins 10, the posts 14 being appropriately perforated for the purpose. There are also provided an appropriate number of spacing strips or bars 16 having a series of passages or perforations 17 corresponding to the perforations 5^a of the strips 4. Some of the spacing bars 16 are of the same length as the strips 4 and in such case may be threaded upon the posts 7 when the passages 17 will match the passages 5^a. There are also provided other spacing bars 16^a which may be of shorter length than the bars 16, but have similar perforations 17 similarly spaced apart. There are also provided other posts 18 of suitable lengths adapted to traverse any of the passages 5 or 17. In addition to the parts already named wedges 19 are provided for a purpose which will presently appear.

The gluing clamp structure is made of a size to accommodate the largest piece of work for which it is probable the clamp will be used, while the parts provided for use in connection with a clamp will readily take smaller work. As examples of the class of work for which the clamp is adapted, there is shown a panel door 20 and various groupings 21, 22 and 23 of boards or strips which it is assumed are glued together edge to edge. In the case of the door 20 it is necessary to bring pressure thereupon both laterally and longitudinally thereof. As the door in the particular structure shown approximates in size the largest article for which the clamp is designed, it is laid upon the strips 4 within the space defined by the posts 7 and 14. Now, wedges 19 are driven between one edge of the door frame and the posts 7 adjacent to said edge, thus clamping the door frame between the several posts 7. Also, a wedge is driven between one of the posts 14 and the corresponding end of the door, thus clamping the other end of the

door against the other post 14. Before the wedges are driven up tight an appropriate number of strips 16 are threaded upon the posts 7 and rest upon the door 20, and then a series 21 of boards or strips glued together are placed upon the lodged spacing strips 16. These boards are assumed to be glued together along their longitudinal edges, and may furthermore be assumed to be as long as the spaces between the end strips 4. Similarly other spacing strips 16 and glued groups 22 are piled upon the parts already in place. It may be that a shorter length 23 of glued strips is ready for clamping, whereupon but two of the groups of posts 7 adjacent one to the other need be provided with spacing strips 16 in addition to those already in place, and if the width of the group of glued strips be less than the full width of the structure then shorter ones of the spacing strips represented at 16^a may be applied. Such strips, however, will not reach from one post 7 to the other carried by the same strip 4, and hence intermediate shorter posts 18 are inserted in appropriate holes in the spaced strips 16 and traverse corresponding holes in the strip or strips 16^a, thus providing intermediate posts against which wedges 19 may be driven to force the strips engaged by them against the primary posts 7. In this manner a pile of articles being glued together may be included in the one frame with each article spaced from the other by spacing strips 16, and where the pile does not reach to the top of the posts 7 braces 24 are applied to the then topmost strips 16 and 16^a, being nailed thereto by nails 25, while the other ends of the braces 24 lodge under respective pins 10. The purpose of the strips 24 is to prevent buckling of the topmost spacing bars 16 or 16^a, and these braces also prevent buckling of the lower strips 16. The wedges are driven between the parts to be glued and the respective posts, so that the parts to be glued are brought into close engagement to there remain so long as may be needed to effect the gluing together of the parts.

With the present invention it is possible to assemble and hold in clamped relation a large number of pieces being glued together while the whole assembled structure takes relatively small space and eliminates wholly the great multiplicity of clamps heretofore required in shops or other places where a large amount of gluing is being constantly performed. Moreover, the gluing clamp is susceptible of manufacture at low cost and in practice is found equally efficient with and oftentimes more efficient than the customary forms of clamps employed in wood working.

The clamp of the present invention has the advantage that it permits the use of wedges which not only constitute an ex-

tremely simple form of pressure means, but provides elongated bearing surfaces upon the work, thus avoiding the liability of denting or otherwise marring the work. The clamp structure also has the advantage of providing for the gluing of both wide and narrow groups of strips or boards at the same time. This is brought about by the use of supplemental posts 18 and either shorter perforated strips 16^a or full length perforated strips 4, and 16, since the supplemental posts may be erected anywhere along the strips between the end posts 7 carried by the strips 4 or 16 or both. Since the additional or supplemental beams 13 and 15 for bringing end pressure to bear upon some structures may be placed anywhere with respect to the width of the gluing frame, it is quite possible to use two or more of such end pressure means, although in most instances a single end pressure structure will be sufficient, and, moreover, need not interfere in any manner with the use of the remaining portion of the structure for clamping smaller groupings during the gluing operation.

What is claimed is:—

1. A gluing clamp structure, comprising a relatively rigid basic frame, a plurality of cross strips carried by the basic frame, and posts carried by each cross strip and adjustable lengthwise thereof, each post being of a length to receive other cross strips like those first-named to provide a series of superposed clamps.

2. A gluing clamp structure, comprising a relatively rigid basic frame, a plurality of cross strips mounted on the basic frame and each movable therealong in a direction perpendicular to the length of the cross strips, and posts carried by each cross strip and adjustable lengthwise of the latter, each post being of a length to receive other cross strips like those first-named to provide a series of superposed clamps.

3. A gluing clamp structure, comprising a relatively rigid basic frame having parallel side sills each with a longitudinal groove along its inner edge, cross strips adapted to the top of the frame and provided with angle brackets entering the grooves, whereby the strips are adjustable lengthwise of the frame, and said strips being each provided with a longitudinal series of perforations, and posts adapted to the perforations and carried by the cross strips, whereby the posts are adjustable lengthwise of the cross strips to thereby vary the distance between the posts.

4. A gluing clamp structure comprising a relatively rigid frame made up of side sills and connecting cross pieces fast to the under sides of the sills, other cross pieces on top of the sills and adjustable lengthwise of the latter, said latter cross pieces each

having a longitudinal series of perforations, posts adapted to the perforations and carried by the cross pieces, and another frame composed of top and bottom beams and end posts connecting them, one of the beams of the second-named frame being adapted to the spaces between the cross pieces of the basic frame and the perforated cross pieces.

5. A gluing clamp structure, comprising a relatively rigid frame made up of side sills and connecting cross pieces fast to the under sides of the sills, other cross pieces on top of the sills and adjustable lengthwise of the latter, said latter cross pieces each having a longitudinal series of perforations, posts adapted to the perforations and carried by the cross pieces, and another frame composed of top and bottom beams and end posts connecting them, one of the beams of the second-named frame being adapted to the spaces between the first-named cross pieces of the basic frame and the perforated cross pieces, and the clamping structure also including perforated spacing strips corresponding to the perforated cross pieces and supplemental posts adapted to the perforations of any of the perforated strips.

6. A gluing clamp structure comprising a relatively rigid frame made up of side sills and connecting cross pieces fast to the under sides of the sills, other cross pieces on top of the sills and adjustable lengthwise of the latter, said latter cross pieces each having a longitudinal series of perforations, posts adapted to the perforations and carried by the cross pieces, and another frame composed of top and bottom beams and end posts connecting them, with one of the beams adapted to the spaces between the cross pieces of the basic frame and the perforated cross pieces, the clamping structure also including perforated spacing strips corresponding to the perforated cross pieces and supplemental posts adapted to the perforations of any of the perforated strips, and the posts and certain of the perforated strips having matching perforations for the reception of locking pins.

7. A gluing clamp structure comprising a relatively rigid basic frame, post carrying members mounted on the frame for adjustment therealong and with respect to which the posts are also adjustable, and spacing strips conforming to the post carrying members and provided with series of perforations for the threading of the spacing strips upon the posts in different positions of adjustments of the latter.

8. A gluing clamp structure comprising a relatively rigid basic frame, post carrying members mounted on the frame for adjustment therealong and with respect to which the posts are also adjustable, and spacing strips conforming to the post carrying members and provided with series of perfora-

4
tions for the threading of the spacing strips upon the posts in different positions of adjustments of the latter, said clamping structure also including a clamping frame 5 extending lengthwise of the basic frame and movable crosswise thereof to different positions of adjustment.

9. A gluing clamp structure comprising a relatively rigid basic frame, post carrying members mounted on the frame for adjustment therealong and with respect to which the posts are also adjustable, and spacing strips conforming to the post carrying members and provided with series of perforations 10 for the threading of the spacing strips upon the posts in different positions of adjustment of the latter, said clamping structure also including a clamping frame 15 extending lengthwise of the basic frame and movable crosswise thereof to different positions of adjustment, and said last-named clamping frame comprising longitudinal beams and connecting end posts.

10. A gluing clamp structure comprising a relatively rigid basic frame, a plurality of 20 clamp frames mounted on and adjustable lengthwise of the basic frame and also adjustable for length crosswise of the basic frame, and another clamp frame separate 25 from and independent of the first-named clamp frames and extended lengthwise of the basic frame for a distance greater than

the distance between two of the first-named clamp frames.

11. A gluing clamp structure having 35 means for exerting pressure individually upon a pile of different groups of material being glued with the pressure exerted in substantially the same direction upon all the groups, and means for exerting pressure 40 upon one or more of the groups in directions substantially perpendicular to the first-named pressure.

12. A gluing clamp structure comprising a basic frame of fixed contour, clamp frames 45 mounted thereon and adjustable along the first frame and also adjustable crosswise of the first-named adjustment to accommodate structures of different widths being glued, and another clamp structure carried by the 50 main frame and provided with means for clamping the structures carried by the first-named clamping means to exert pressure thereon in directions substantially perpendicular to the direction of pressure exerted 55 by the first-named clamping means.

In testimony that I claim the foregoing as my own, I have hereto affixed my signature in the presence of two witnesses.
